UNITED STATES PATENT OFFICE.

ELMER L. SCHUMACHER, OF SOUTHBIDGE, AND WILLIAM H. BOUTELLE, OF STURBRIDGE, MASSACHUSETTS, ASSIGNEES TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

Application filed March 6, 1922. Serial No. 541,523.

To all whom it may concern:

Be it known that we, ELMER L. SCHUMACHER and WILLIAM H. BOUTELLE, citizens of the United States, residing at Southbridge and Sturbridge, respectively, in the county of Worcester and State of Massachusetts, have invented certain new and useful Improvements in Ophthalmic Mountings, of which the following is a specification.

10 This invention relates to improvements in ophthalmic mountings, and has particular reference to a novel and improved construction of metallic reinforcement and hinged joint for composition or non-metallic frames.

One of the principal objects of the present invention is the provision of an improved metallic member for use in a composition or non-metallic frame, which will provide a large and durable hinge joint or connection and at the same time a satisfactory brace for the non-metallic member itself.

A further object of the present invention is the provision of a structure of this character in which means are employed for holding the back portion of the zylonite or other composition from separation or spreading relative to the hinge joint.

A further object of the present invention is the provision of an improved process or method of manufacture by which the results in question can be attained to a maximum degree.

Other objects and advantages of our improved construction should be readily apparent by reference to the following specification taken in connection with the accompanying drawings, and it will be understood that any modifications in the specific details of construction shown and described may be made within the scope of the appended claims without departing from or exceeding the spirit of the invention.

Figure I is a front view of a mounting embodying the improvements.

Figure II is a plan view thereof.

Figure III is a sectional view as on the line III—III of Figure II.

Figure IV is a sectional view as on the line IV—IV of Figure III.

Figure V is a sectional view as on the line V—V of Figure IV.

Figure VI is a detailed view of one of the metallic members.

Figure VII is a similar view of the other metallic member before uniting.

Figure VIII is a fragmentary view of the composition frame member illustrating one step in the process of manufacture.

Figure IX is a further step.

Figure X is a slight modification of the structure shown in Figure VIII.

Figure XI is a detail prospective of the body member 5 with the barrel 8 attached.

In the drawings, the numeral 1 designates a composition bridge having integral therewith the lens receiving portion or eyes 2 provided with the end piece projections 3, the whole forming what is termed in the art a front. These end piece portions 3 are rearwardly deflected as is clearly shown in Figure II, for example, and have suitably engaged thereto the temple members 4 for retaining the mounting in position on the face.

The improvement here in question relates particularly to the method or means by which the hinged joint is maintained a firm one. In the accomplishment of this result

use is made of a metal prong plate, which may be stamped from sheet material, for example, having a body 5 with slight prongs 6 at one side and elongated pliable prong like members 7 at the opposite side. This body member 5 may have suitably secured thereto

as at 5^a the bifurcated sleeve or barrel member 8 having the frustro-conical end portions 9. Just prior to the final fastening of the barrel 8 to the body member or at any suitable time, the prongs 6 are de-

flected, or upset, to one side in the manner shown in Figure XI and in attaining the attachment of these two parts the metal of the body member 5 is suitably shaped in order that the attached parts will ap-

pear as in Figure XI. The two metallic members having been secured together they are in shape for introduction into

the end piece 3. To facilitate its introduction, as well as the subsequent formation of the parts the end piece is milled or cut

away on its rear or inner surface, as at 10, in a wide sweeping arc or curve whose radius

is greater than the radius of the barrel 8.

Preferably subsequent to this milling the end piece also has formed therethrough apertures or passages 11. The parts of the composition frame and the metallic parts 5 having been suitably prepared, the prongs 7 are then forced inward through the passages 11, as by the use of a suitable die or pressing tool 12, while the frame itself is held on the support or block 13 having 10 the bevelled portion 14 fitting into the lens receiving groove 15 and having a slight edge groove as at 16. This groove projects beneath the inner mouth of the passage 11 so that as the terminally reduced 15 points 17 of the prongs start to come out and project into the interior of the rim they will strike into these grooves and be deflected and bent backward, as is clearly illustrated in connection with Figure V. 20 Due to this action the metallic member and the hinge barrel 8 carried by it are most securely retained in place.

It is to be noted by reference to Figure IX that when forced into place the barrel 8 lies 25 not at the edge or terminus of the end pieces 3 but intermediately of the length of the milled or cut away portion 10. The purpose of this will be understood by reference to Figure IV, in which the end piece is 30 shown formed into its final condition.

Prior to the present invention similarly formed end pieces have been employed but difficulty has been experienced due to the fact that in bending or shaping the end 35 piece there is a compression of the material inside the bend and a stretching of the outside material so that it is difficult to get the parts into proper position and there maintain them even with metallic bend inserts unless cuts or the like relieving the strain by removing a portion of the material 40 are formed.

In the case of the present invention, however, the ratio of the radius of the curve 10 45 to the bend to be formed and the barrel 8 is such that when the barrel 8 and its carrying member 5 with prongs 7 is secured to the end piece and the end piece subsequently bent or shaped the material on the 50 inner part of the end piece being compressed will yield outwardly to form a tight joint with the metal barrel, as indicated at 18 in Figure IV. At the same time the material at the back being stretched and relatively 55 free to yield will be drawn down so that in the final form the barrel 8 in place of being intermediate the length of the milled or cut away portion will be substantially on line with the terminal edge or end of the 60 end piece lug.

To best hold the parts together, particularly this terminal portion of the end piece lug and the metallic member and prevent 65 pulling away the prongs 6 supplemented if desired by a prong 20 are employed. These

prongs are slightly rearwardly deflected as the die 12 pushes the metallic member into the zylonite, as indicated in Figure IX, so that they partially bite in to aid in locking the body 5 in place. As the end piece is 70 bent up the creep of the outer portion of the material forwardly causes it to ride onto these prongs 6 and 20 to become more firmly engaged therewith so that it is impossible to pull loose the barrel 8 at the 75 outer edge of the end piece from the end piece material itself.

At any suitable time during the process of manufacture, but preferably after the parts have been thus united, the member 8 80 is centrally slotted to form the recess 21 to receive the metallic hinge portion 22 of the temple 4. The large central portion of the member 8 thus provides wide bearing surfaces to eliminate undue play of the temple and give opportunity for a larger temple joint which will be less liable to break when in use, while at the same time the tapering of the ends of the member 85 renders the exposed portion thereof relatively inconspicuous when the mounting is being handled while, of course, the presence of the material of the end piece lug on the outer side conceals the metal when the mounting is being worn. If desired to still 90 more effectually conceal the metal at all times the end piece instead of being milled on the arc 10 of Figure VIII may be milled on a somewhat corresponding arc 23 as shown in Figure X, with a notched or cut 95 away portion 24 so that as the material is bent the outer portion may be drawn downwardly and the inner portion which has a tendency to be compressed by the bending 100 will naturally spring up around the member 4 and will cause it to be more satisfactorily 105 and entirely covered and concealed.

It is to be understood that the member 5 and associated parts is preferably forced into the composition zylonite or other non-metallic material while the same is heated so that it will readily yield to the entrance of the metallic parts and also to the clinching over of the ends of the bars. It is further to be understood that the composition 110 member is preferably either retained in this heated condition or subsequently reheated prior to the bending operation to a degree which will render the composition 115 material plastic or mouldable so that as it is bent around to the final shape which it is intended to have it assume the material will have a flowing action so that as compressed at the inner angle of the bend it will 120 flow up around the barrel member 8 and 9 125 to fit tightly thereagainst and therearound to partially conceal the same, while at the same time the outer portion being stretched or drawn will have a tendency to flow in the direction in which it is stretched so as to 130

more firmly interengage with the prongs 6 and 20 so that the parts will best assume the relation shown in detail in Figure IV and when chilled will tend to remain in 5 that position and to be held in that position on account of the contained metal arms 7.

We claim:

1. The process of producing an ophthalmic frame consisting in cutting away a portion 10 of a composition end piece, securing a metallic member to the end piece and within the cut away portion, and subsequently bending the combined parts whereby the material of the end piece is caused to shift 15 relative to the metallic member and partially enclose the same.

2. The process of forming an ophthalmic mounting consisting in securing a pronged metallic member within a composition member with certain relatively free prongs, and bending the parts to stretch the composition 20 over the free prongs to tightly interlock therewith.

3. The process of producing a combination 25 ophthalmic mounting consisting in forming a composition end piece with a cut away portion, intermediately seating a metallic hinge member in said cut away portion and combining the parts under the influence 30 of heat to cause the composition member to flow around and partially embrace the metallic member.

4. The process of producing a combination 35 ophthalmic mounting consisting in forming a composition end piece with a cut away portion, intermediately seating a metallic hinge member in said cut away por-

tion, combining the parts under the influence of heat to cause the composition member to flow around and partially embrace the metallic member, and slotting a portion of the metallic member after its engagement in the non-metallic member to provide a temple receiving recess. 40

5. The process of forming an ophthalmic 45 mounting consisting in shaping a piece of sheet stock with a central body portion, and prongs projecting from both sides thereof, securing a tube to said body portion, inserting one set of prongs in a non-metallic 50 end piece, and bending the combination article to draw the composition material into tight engagement with the other set of prongs.

6. An ophthalmic mounting, comprising 55 a composition frame having an end piece, a hinge member comprising a bifurcated barrel portion extending beyond the end piece, and a bifurcated prong plate, the plane of whose face is parallel to the axis 60 of the barrel, extending into the end piece, and an additional prong at an angle to the prong plate, and a second hinge member carrying a temple pivotally mounted in 65 the bifurcation of the barrel.

7. The process of inserting a metallic tongue of a hinge member into the end piece of a composition ophthalmic mounting, and thereafter bending both the metallic tongue 70 and composition end piece to anchor the tongue against displacement along the line of its entrance.
